UNITED STATES PATENT OFFICE.

ARTHUR A. JOHNSON, OF LYNDHURST, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,302,169.

Specification of Letters Patent. Patented Apr. 29, 1919.

Application filed October 3, 1917. Serial No. 194,441.

To all whom it may concern:

Be it known that I, ARTHUR A. JOHNSON, a citizen of the United States, residing in Lyndhurst, in the county of Bergen and 5 State of New Jersey, have invented certain new and useful Improvements in Type-Writing Machines, of which the following is a specification.

My invention relates to typewriting machines, and is herein disclosed as applied to 10 an Underwood typewriting machine having a carriage, which comprises a number of features similar to the Underwood fan-fold typewriter, in which the typewriter carriage 15 carries an extension adapted to preserve the proper alinement of the carbon sheets and the fan-fold web, and also is adapted to facilitate their handling.

In such machines, it has hitherto been 20 common to provide a platen which could be swung up far above its usual position on the typewriter carriage, in order to enable the fan-fold web together with the carbon sheets therebetween to be stretched out practically 25 straight, so as to permit the carbon sheets to be readjusted relatively to the web. This stretching straight of the fan-fold web has hitherto been a feature of such machines, because it is well known that it is impossible 30 to slide carbon sheets relatively to work-sheets in a round platen machine of the front-strike type, owing to the fact that when carbon sheets lie between work-sheets, the adhesion is sufficient to prevent the sheets 35 from being moved to any large extent relatively to each other, because the curve in all ordinary front-strike typewriting machines covers too great and too sharp an arc to permit this. Such difficulty of readjusting the 40 carbon sheets becomes prohibitive with even a smaller arc if the carbon sheet has made impressions on the work-sheet, since the making of such impressions results in some adhesion between the carbon sheet and work- 45 sheet. These difficulties in still smaller arcs are increased with the number of carbon and work-sheets which lie around the platen at any given time to such an extent that when as many as three carbon sheets are employed 50 the carbon sheets are practically locked to the other sheets, unless almost stretched straight.

According to my invention, the carbon

sheets may be led in between a plurality of sheets, such as the various plies which make up the ordinary fan-fold web, and the carbon sheets may be led out from between such work-sheets, both the leading in and leading out being done at points where the work-sheets are substantially straight. This permits me to adopt a structure which will enable the carbon sheets to be in the form of loops or endless or continuous belts, which have bights reaching into the fan-fold web traveling along with it, then reaching out from the fan-fold web and traveling back to the point of reentering, with the result that a loop or belt will take care of itself during any ordinary day's or week's writing, without any need of manual manipulation of the carbon sheets, and there need be no occasion for swinging up the platen. To accomplish this and other results, I preferably use an extension on the rear of the typewriter carriage analogous to the extension used in the Underwood fan-fold typewriters, so that the fan-fold web comes forward over said extension substantially horizontally, and while horizontal has the carbon sheets led into it by suitable turning devices, such as V-shaped plates. The carbon sheets and the fan-fold web then travel along together around the platen of the typewriter and up in front of the platen, at which latter point a second set of carbon-turners or guides or V-shaped plates may lead the carbon sheet away from the web, so that the latter may be then torn off without any danger of tearing the carbon sheet.

To provide for this tearing off, there may be a knife above the platen forming part of a frame adapted to support the carbon-sheet guides. To permit easy threading of the carbon sheets, especially when inserting a continuous band into the folds of the fan-fold web, the typewriter platen may be removable, and suitable holding devices for the web may be provided.

Other features and advantages will hereinafter appear.

In the accompanying drawings,

Figure 1 is a perspective view of an Underwood typewriting machine carriage, showing my invention as applied thereto.

Fig. 2 is a detail, showing how the platen may be removably mounted.

Fig. 3 is a perspective view, showing the course of the webs and carbon sheets in Fig. 1.

Fig. 4 is a detail of one form of edge for a carbon sheet.

The typewriter carriage 1 is, in many respects, of the ordinary Underwood form, including a frame 2 and a platen 3; the latter journaled in the ends 4 and 5 of the frame 10 on an axle 6, and adapted to be rotated by the usual line-space mechanism, which comprises the handle 7. Behind the platen is the usual paper-table 8 having extensions 9, which come under and around in front of the 15 platen to form guides. Also associated with the platen are the front and rear feed rolls 10 and 11 provided with the usual release mechanism, which includes a shaft 12 and a handle 13 for operating it. As the typewriter travels along the main frame of the machine (not shown), it carries along with it a rearward extension, which includes side bars 14 and 15 united at the rear by a cross-bar 16, over which a fan-fold web 17 is 20 adapted to be drawn. The web 17 is guided on the cross-bar 16 by means of adjustable side gages 18, and comes forward above a second cross-bar 19, beneath a locking arm 20, and then passes over the paper-table 8 25 down beneath the platen 3 and up in front, where it is adapted to be written on by the usual types 21.

The fan-fold web 17 includes a top ply or sheet 22, a bottom sheet 23, a top intermediate sheet 24 and a bottom intermediate sheet 25, all of which are usually provided with nearly identical forms of a given definite length which are to be filled out; the original 23 by the type 21, and the other 30 copies to be filled out by carbon impressions made while the type 21 strikes on the original 23. Between the cross-bar 16 and the second cross-bar 19 the fan-fold web 17 passes angle-plates 26, 27 and 28, which are 35 adapted to guide carbon sheets 29, 30 and 31 in between the plies 22, 23, 24 and 25 of the fan-fold web, so that the aforesaid carbon copies may be made. Since the fan-fold sheet has some of its folds 29^a at one 40 edge and some at the other, the angle plates have to be correspondingly positioned, with the result that the plate 26 guides the carbon sheet 29 between the plies 24 and 25. The angle plate 27 guides the carbon sheet 45 30 between the plies 22 and 24, while the angle plate 28 guides the carbon sheet 31 between the plies 25 and 23. In order to do this guiding effectively, said angle plates are each provided with an extension 32, 50 which is adapted to engage a pin 33 or 34 fast on the side bars 15 or 14. The angle plates are further steadied by pins 35 and 36 also fast to said side bars; each pin 55 adapted to engage and fit closely in a cor-

responding hole in the extension 37 of the 65 angle plate.

In order to properly introduce the carbon sheets, the angle plates 26, 27 and 28 are each provided with a face 38 set at an angle of 45° to the line of travel of the fan-fold web 17, said face 38 lying toward the outer side of the typewriter carriage extension; and the angle plates are also provided with a second face 39, also at an angle of 45° to the line of travel of the web 70 17, and adapted to turn the course of a carbon sheet coming over the angle plates 26, 27 and 28 at right angles to the line of travel of the web 17, so that after passing the face 39 the carbon sheet will travel 75 80 smoothly in line with the web 17.

When all three carbon sheets 29, 30 and 31 are properly threaded over the angle plates 26, 27 and 28, so that they all turn the face 39 properly, the carbon sheets and 85 the fan-fold web will fit smoothly around the platen past the printing point opposite the position of the type 21 in Fig. 3, and then the fan-fold web and the carbon sheets, in passing upward, encounter a second set 90 of angle plates 40, 41 and 42, each of these being provided with an edge 43 set at an angle of 45° to the line of travel of the web. If the web is properly threaded between the plates 40, 41 and 42, the edge 43 95 will lie adjacent each carbon sheet, with the result that each carbon sheet can be turned around the adjacent edge 43 and led out at right angles to the line of travel of the web toward the end of the typewriter carriage. 100

The web 17 travels on upwardly behind a knife 44, which is supported on standards 45 and 46 rising from opposite ends of the usual frame, in which the platen 3 is more or less directly journaled. The standards 45 105 and 46 are inclined somewhat rearwardly so that the web 17, as it travels upward toward the knife 44, has a rearward slant, making it easy to read characters thereon.

Behind the knife 44 and spaced therefrom by spacing blocks 47, but firmly attached thereto and to the standards 45 and 46, is a cross-bar 48 adapted to support the rear side of the web, and carrying an upward extension 49 forming a support for an 110 adjustable end gage 50 of a type common in fan-fold machines. With this structure, the knife 44 forms a convenient edge along which to tear off the web 17, and by setting the end gage 50 at the right height, the 115 operative need pay no attention to measuring by the eye the point at which the web 17 is to be adjusted along the knife 44, but the position of the gage 50 will enable the 120 end of the web 17 to be positioned thereagainst by feeling and then the web to be 125 torn off.

The angle plates 40, 41 and 42 are advan-

- 5 tageously removably mounted on the standards 45 and 46, so that they can be taken out to enable continuous belts of carbon sheets to be adjusted therearound. To enable the angle plates 40, 41 and 42 to be thus mounted, there is provided a threaded thumb-screw 51 adapted to be inserted in a threaded opening 52 near the top of the angle plates 40, 41 and 42, and this thumb-screw 10 is adapted to pass through openings in the angle plates. To enable these angle plates to be spaced with their faces apart from each other, the screw 51 is adapted to pass through spacing collars 54, which are 15 of such a length that the plate 41 is spaced away from the support 46 on which it is mounted. The plate 40 is spaced slightly behind and clear of the plate 41, and the plate 42 is spaced behind both the plates 20 40 and 41, with the result that the web 17 may have a plate between each of its folds adjacent the carbon sheet within that fold. In order to steady the lower ends of the angle plates 40, 41 and 42, they are provided with extensions 55, through which 25 thumb-screws 56 are adapted to pass, said thumb-screws also being provided with spacing collars 54 to preserve the same spacing at the bottom as at the top of the angle 30 plates 40, 41 and 42. The outer ends of the angle plates 40, 41 and 42 may be steadied by horizontal extensions 57 projecting from the bases 58 by which the standards 45 and 46 are attached to the 35 platen frame. In addition to the internal 45° edge 43, the angle plates 40, 41 and 42 have external edges 59 about which the carbon sheets are adapted to be turned to lead the carbon sheets downwardly.
- 40 Rolls 60 journaled in ears 61 on the extensions 57, and in ears 62 on the standards 45 and 46, are provided below the bottoms of the angle plates 40, 41 and 42 to permit the carbon sheets to be guided therearound, 45 so that after coming down across the faces of the plates 40, 41 and 42, the carbon sheets may extend rearwardly along their bights 63, seen in Fig. 3. The rearwardly-extending bights 63 of the carbon sheets then turn 50 around the 45° faces 38 of the angle plates 26, 27 and 28, which are adapted to turn the sheets horizontally toward the center of the carriage, with the result that they will be able to turn around the faces 39 and feed 55 along again with the web 17. In order to keep the plates 26, 27 and 28 spaced apart from each other, there may be provided suitable spacing sleeves 65, through which the pins 33, 34, 35 and 36 pass.
- 60 The carbon sheets in an ordinary fan-fold machine are usually sufficient for a day's writing, and since a carbon belt for use in the present invention is upward of six times as long as that used in the fan-fold machine,

one carbon sheet belt a week is usually sufficient. 65

It will be usually found advantageous to have the knife about the height of a "form" above the printing point, so that the machine will usually have left in it the form last 70 written on, while the form written previously to that one has been torn off by the knife 44.

The carbon sheet or belt may be advantageously strengthened, as diagrammatically 75 shown in Fig. 4, by having a reinforcing strip 66 embrace the sheet 67 proper. The carbon sheet or belt may advantageously be in the form of an exceedingly thin carbonized fabric having a silky feeling, such as 80 is now obtainable on the market. The ends of the carbon belt may be united in any suitable manner. It will sometimes be found advantageous "to break joints" (see 64) where the carbon sheet has the binding 66 85 around it. This will result in having a sheet which is strengthened by the binding 66 at the point where it is weakest from its own joint.

If the platen of the typewriter is made removable, as illustrated in Fig. 3, it is unnecessary for the typist to make any joints in the carbon sheet, but may utilize any continuous carbon sheet which is available and of the right length. The length advantageously is such that in passing around the platen a second time, the line of writing on the carbon sheet will not coincide with the line of writing which was written on at the first time, for reasons well known to those 100 accustomed to using carbon sheets. 90

In order to remove the platen, the structure as shown in the patent to Gruner, No. 1,177,031, dated March 28, 1916, may be utilized, in which the platen axle is interrupted 105 near the end plate 68 of the platen frame, and ends in a tongue 69 adapted to enter a corresponding recess 70 in a stub shaft 71, slidably journaled in the end plate 68. In order to hold the platen normally in place, the stub shaft 71 is held so that the projecting ends 72 thereof on the opposite sides of the recess 70 lie within the platen, this being accomplished by causing a keeper 73 to enter a slot 74 in the axle. This keeper is 110 rotatably pivoted on a bracket extending from the frame 68, and is adapted to be thrown into and out of effective position by a handle 75 mounted on a pivot 76 and connected by a link 77 to said keeper, thus enabling the keeper to be lifted clear of the platen axle, with the result that when this is done, the platen axle can be slid endwise and then the platen lifted from the stub shaft, the platen for this purpose having a 115 somewhat similar stub shaft and a tongue-and-groove connection at the opposite end.

When the platen is removed, a carbon

sheet may be laid around the bottom angle plate 28, the plate for this purpose being lifted clear from one of its pins, and then the carbon sheet may be threaded around 5 the front plate 41, pass down to the place where the platen would normally be, and then up over the paper-table 8, over the cross-bar 19 and around the inner angle of the angle plate 28, said plate being for this 10 purpose again raised from the pins if necessary to obtain the requisite looseness of the carbon sheet.

It will be observed that the belt, which forms the carbon sheet, is so threaded around 15 the angle plates and rollers that the carbon surface never touches or slides over any fixed plate, and, in fact, it is only in turning the rollers 60 that the carbon faces touch anything except the work-sheet. In order to 20 enable any carbon sheet to pass around its roller 60, said roller is removable, and for this purpose is slidably journaled at 78 in the adjoining upright 45 or 46, and has its outer axis 79 journaled in a slot 80 in the 25 ear 61, and is held in the slot by a spring, past which it can be sprung when being removed.

In order to form a guide for the free end or free fly of the web 17, which might otherwise fall behind the plate or bar 48, the lower end of the plate 48 is extended downwardly, as shown at 82, to form a guide therefor. In machines adapted to use thin 30 work-sheets, it may be found advantageous 35 to carry said guide 82 downwardly as far as it can conveniently be carried without seriously interfering with the operation of threading the carbon sheets or belts around the angle plates 40, 41 and 42. The guide 40 45 may extend rearwardly also, if desired, for the same purpose. The plates 40, 41 and 42 and the extension 82, therefore, practically form guides for the work-sheets forming the web 17, as it rises upwardly 50 from the platen.

In order to enable the work-sheets to lie as snugly as possible against the knife 44, the opening between the knife 44 and the bar 48, while wide enough to allow easy 55 slipping of the work-sheets, should not be wide enough to allow the work-sheets to fall into deep bends therein.

While one method of threading the carbon sheets or belts has been described, various 55 typists will undoubtedly find that other methods of threading them come naturally to them, but in general it will be found advisable to always thread the sheets in substantially the same manner so as to cultivate 60 a proper habit of doing the work, with the result that it can be done more rapidly after a little practice.

In order to facilitate the threading of the carbon sheets and the web, the locking arm

20 may be swung down to catch the margin 65 of the web (or carbon) against the cross-bar 19, said arm for this purpose being pivoted on the side-bar 15, and having a spring 83 which is adapted to hold it at the limit of its throw in each direction. 70

A stop 84 limits the throw of the arm 20 away from the bar 19. To prevent the carbon sheet from running into folds, the 45° edges of the angle plates 26, 27, 28, 40, 41, 42 may be slightly crowned. 75

Variations may be resorted to within the scope of the invention and portions of the improvements may be used without others.

Having thus described my invention, I claim:

1. In a typewriting machine, the combination with a traveling carriage and a rotating platen thereon, of means for guiding work-sheets around said platen, means for guiding separate sheets in between said work-sheets at points near the platen, and means for automatically removing said last-named sheets after the whole body of sheets has passed together around the platen. 80 85

2. In a typewriting machine, the combination with a traveling carriage and a rotating platen thereon, of means for guiding work-sheets around said platen, means for guiding separate sheets in between said work-sheets at points near the platen, means for automatically removing said last-named sheets after the whole body of sheets has passed together around the platen, and a knife adapted to sever the sheets from which 90 95 said sheets were removed. 100

3. In a typewriting machine, the combination with a traveling carriage and a rotatable platen therein, of devices adapted to cause work-sheets to feed around said platen, devices adapted to feed carbon sheets 105 in between said work-sheets, so that the carbon sheets and the work-sheets feed together around the platen, means for automatically removing said carbon sheets from between said work-sheets when the work-sheets have 110 passed beyond the printing point, a knife adapted to sever said work-sheets after the carbon sheets have been removed from there-between, and a gage beyond the knife adapted to form a limiting stop for the end of said 115 work-sheets to measure the point at which they are severed by said knife.

4. In a typewriting machine, the combination with a traveling carriage and a rotatable platen therein, of means for holding work-sheets against said platen, angle plates adapted to feed carbon sheets in between said work-sheets and having an edge at an angle to permit carbon sheets to be fed to said work-sheets in a line parallel to the 120 travel of said platen, and a second set of angle plates extending between said work-sheets beyond the printing point at the 125

platens and comprising an edge at an angle adapted to lead carbon sheets away from said work-sheets.

5. In a typewriting machine, the combination with a traveling carriage and a rotatable platen therein, of means for holding work-sheets against said platen, angle plates adapted to feed carbon sheets in between said work-sheets and having an edge at an angle 10 to permit carbon sheets to be fed to said work-sheets in a line parallel to the travel of said platen, a second set of angle plates extending between said work-sheets beyond the printing point at the platen and comprising an edge at an angle adapted to lead carbon sheets away from said work-sheets, a knife above said last-named angle plates adapted to form a severing edge for severing the work-sheets, and a gage beyond 15 said knife adapted to indicate the point at which said work-sheets will be severed by said knife.

6. In a typewriting machine, the combination with a traveling carriage and a rotatable platen therein, of devices for causing work-sheets to feed around said platen, an extension in the rear of said platen adapted to convey a continuous work-sheet to said platen, angle plates on said extension adapted to convey carbon sheets in between said work-sheets, a second set of angle plates extending between said work-sheets beyond the printing point at said platen, adapted to lead said carbon sheets away from said 30 work-sheets, and supporting means adapted 35 to hold said work-sheets while said carbon sheets are being so diverted and after they are diverted.

7. In a typewriting machine, the combination with a traveling carriage and a rotatable platen therein, of devices for causing fan-fold work-sheets to feed around said platen, edge guides for said fan-fold work-sheets as they approach the platen, angle plates extending into said fan-fold sheets 40 adapted to convey carbon sheets therebetween and to turn them to move parallel to said fan-fold sheets, angle plates beyond 45 the printing point of said platen adapted to divert said carbon sheets from said fan-fold sheets, and a severing device adapted to sever said fan-fold sheets.

8. In a typewriting machine, the combination with a traveling carriage and a rotatable platen thereon, of means for guiding work-sheets around said platen, means for guiding separate sheets in between said work-sheets at points near the platen, means for automatically removing said last-named 50 sheets after the whole body of sheets has passed together around the platen, and means for guiding said separate sheets after being removed back into position to be again guided between said work-sheets.

9. In a typewriting machine, the combination with a traveling carriage and a rotatable platen thereon, of means for guiding work-sheets around said platen, means for guiding separate sheets in between said work-sheets at points near the platen, means 65 for automatically removing said last-named sheets after the whole body of sheets has passed together around the platen, a knife 70 adapted to sever the sheets from which said sheets were removed, and means for guiding 75 said separate sheets after being removed back into position to be again guided between said work-sheets.

10. In a typewriting machine, the combination with a traveling carriage and a rotatable platen therein, of devices adapted to cause work-sheets to feed around said platen, devices adapted to feed carbon sheets in between said work-sheets, so that the carbon sheets and the work-sheets feed together 80 around the platen, means for automatically removing said carbon sheets from between said work-sheets when the work-sheets have passed beyond the printing point, a knife 85 adapted to sever said work-sheets after the carbon sheets have been removed from therebetween, a gage beyond the knife adapted to form a limiting stop for the end of said work-sheets to measure the point at which they are severed by said knife, and means 90 for feeding said carbon sheets after being removed back to the devices adapted to feed the carbon sheets between the work-sheets.

11. In a typewriting machine, the combination with a traveling carriage and a rotatable platen therein, of means for holding work-sheets against said platen, angle plates adapted to feed carbon sheets in between 100 said work-sheets and having an edge at an angle to permit carbon sheets to be fed to said work-sheets in a line parallel to the travel of said platen, a second set of angle plates extending between said work-sheets 105 beyond the printing point at the platen and comprising an edge at an angle adapted to lead carbon sheets away from said work-sheets, and means for feeding said carbon sheets after being removed back to the devices adapted to feed the carbon sheets between the work-sheets.

12. In a typewriting machine, the combination with a traveling carriage and a rotatable platen therein, of means for holding work-sheets against said platen, angle plates adapted to feed carbon sheets in between 110 said work-sheets and having an edge at an angle to permit carbon sheets to be fed to said work-sheets in a line parallel to the travel of said platen, a second set of angle plates extending between said work-sheets 115 beyond the printing point at the platen and comprising an edge at an angle adapted to lead carbon sheets away from said work-

- sheets, a knife above said last-named angle plates adapted to form a severing edge for severing the work-sheets, a gage beyond said knife adapted to indicate the point at which 5 said work-sheets will be severed by said knife, and means for feeding said carbon sheets after being removed back to the devices adapted to feed the carbon sheets between the work-sheets.
- 10 13. In a typewriting machine, the combination with a traveling carriage and a rotatable platen therein, of devices for causing work-sheets to feed around said platen, an extension in the rear of said platen adapted 15 to convey a continuous work-sheet to said platen, angle plates on said extension adapted to convey carbon sheets in between said work-sheets, a second set of angle plates extending between said work-sheets beyond the 20 printing point at said platen, adapted to lead said carbon sheets away from said work-sheets, supporting means adapted to hold said work-sheets while said carbon sheets are being so diverted and after they are 25 diverted, and means for feeding said carbon sheets after being removed back to the devices adapted to feed the carbon sheets between the work-sheets.
14. In a typewriting machine, the combination with a traveling carriage and a rotatable platen therein, of devices for causing fan-fold work-sheets to feed around said platen, edge guides for said fan-fold work-sheets as they approach the platen, angle 30 plates extending into said fan-fold sheets adapted to convey carbon sheets therebetween and to turn them to move parallel to said fan-fold sheets, angle plates beyond the printing point of said platen adapted to divert said carbon sheets from said fan-fold sheets, a severing device adapted to sever 35 said fan-fold sheets, and means for feeding said carbon sheets after being removed back to the devices adapted to feed the carbon sheets between the work-sheets.
- 40 15. In a typewriting machine, the combination with a traveling carriage and a rotatable platen therein, of an extension extending rearwardly from said carriage adapted to guide work-sheets to the platen, devices 45 adapted to guide other sheets between said work-sheets from a direction parallel to the line of travel of the carriage, another extension on said carriage extending upwardly therefrom adapted to guide said other sheets away from said work-sheets, and comprising holding means adapted to hold the written work-sheet in view of the typist, and a knife for severing said work-sheets.
- 50 16. In a typewriting machine, the combination with a traveling carriage and a rotatable platen therein, of an extension extending rearwardly from said carriage adapted to guide work-sheets to the platen, 55 detachable angle plates mounted on said rearward extension adapted to permit carbon sheets to be led in between said work-sheets, an upward extension of said carriage, 60 adapted to guide work-sheets to the platen, 65 an angle plate adapted to guide a carbon sheet in between said work-sheets from one side, a second angle plate adapted to guide a carbon sheet in from the other side, an extension mounted on said carriage adapted to 70 lead the written work-sheets away from the platen, an angle plate adapted to lead a carbon sheet away from the work-sheets on the side from which it approached the work-sheets, and a second angle plate adapted to 75 lead a carbon sheet away on the opposite side.
17. In a typewriting machine, the combination with a traveling carriage and a rotatable platen therein, of an extension extending rearwardly from said carriage adapted to guide work-sheets to the platen, an angle plate adapted to guide a carbon sheet in between said work-sheets from one 80 side, a second angle plate adapted to guide a carbon sheet in from the other side, an extension mounted on said carriage adapted to lead the written work-sheets away from the platen, an angle plate adapted to lead a carbon sheet away from the work-sheets on the 85 side from which it approached the work-sheets, and a second angle-plate adapted to lead a carbon sheet away on the opposite side, each angle plate also comprising a second angle, so that a carbon sheet may be led 90 back from the last-named angle plates to the first-named angle plates.
18. In a typewriting machine, the combination with a traveling carriage and a rotatable platen therein, of an extension extending rearwardly from said carriage adapted to guide work-sheets to the platen, an angle plate adapted to guide a carbon sheet in between said work-sheets from one 95 side, a second angle plate adapted to guide a carbon sheet in from the other side, an extension mounted on said carriage adapted to lead the written work-sheets away from the platen, an angle plate adapted to lead a carbon sheet away from the work-sheets on the 100 side from which it approached the work-sheets, a second angle plate adapted to lead a carbon sheet away on the opposite side, each angle plate also comprising a second angle, so that a carbon sheet may be led back 105 from the last-named angle plates to the first-named angle plates, and means for supporting and measuring the work-sheets after the carbon sheets have been removed therefrom.
19. In a typewriting machine, the combination with a traveling carriage and a rotatable platen therein, of an extension extending rearwardly from said carriage adapted to guide work-sheets to the platen, 110 detachable angle plates mounted on said rearward extension adapted to permit carbon sheets to be led in between said work-sheets, an upward extension of said carriage, 115
- 20 120
- 125

- and detachable angle plates mounted on said upward extension adapted to guide said carbon sheets away from said work-sheets.
20. In a typewriting machine, the combination with a traveling carriage and a rotatable platen therein, of an extension extending rearwardly from said carriage adapted to guide work-sheets to the platen, detachable angle plates mounted on said rearward extension adapted to permit carbon sheets to be led in between said work-sheets, an upward extension of said carriage, and detachable angle plates mounted on said upward extension adapted to guide said carbon sheets away from said work-sheets, certain of said angle plates adapted to lead carbon sheets to and from the work-sheets on one side, and others of the angle plates adapted to lead the carbon sheets to and away from the work-sheets on the other side.
21. In a typewriting machine, the combination with a traveling carriage and a rotatable platen therein, of a rearward extension of said carriage, pins mounted on said extension, angle plates removably mounted on said pins, an upward extension of said carriage, a second set of pins upon said upward extension, angle plates for said last-named pins adapted to be removably held thereon, and rolls adapted to bear against the front sides of carbon sheets whose back sides bear exclusively against said angle plates.
22. In a typewriting machine, the combination with a traveling carriage and a rotatable platen therein, of a rearward extension of said carriage, pins mounted on said extension, angle plates removably mounted on said pins, an upward extension of said carriage, a second set of pins upon said upward extension, angle plates for said last-named pins adapted to be removably held thereon, so that fan-fold work-sheet may be drawn forwardly with the angle plates projecting well toward the bottom of its folds, and guides for said fan-fold work-sheet.
23. In a typewriting machine, the combination with a traveling carriage and a rotatable platen therein, of a rearward extension of said carriage, pins mounted on said extension, angle plates removably mounted on said pins, an upward extension of said carriage, a second set of pins upon said upward extension, angle plates for said last-named pins adapted to be removably held thereon, so that a fan-fold work-sheet may be drawn forwardly with the angle plates projecting well toward the bottom of its folds, guides for said fan-fold work-sheet, a knife above the front angle plates, and a gage beyond said knife adapted to serve to measure the length of work-sheet to be severed by said knife.
24. In a typewriting machine, the combination with a traveling carriage and a rotatable platen therein, of a rearward extension of said carriage, pins mounted on said extension, angle plates removably mounted on said pins, an upward extension of said carriage, a second set of pins upon said upward extension, and angle plates for said last-named pins adapted to be removably held thereon, said platen being removable to permit an endless carbon sheet to be threaded around said angle plates and said platen.
25. In a typewriting machine, the combination with a traveling carriage and a rotatable platen therein, of a rearward extension of said carriage, pins mounted on said extension, angle plates removably mounted on said pins, an upward extension of said carriage, a second set of pins upon said upward extension, angle plates for said last-named pins adapted to be removably held thereon, said platen being removable to permit an endless carbon sheet to be threaded around said angle plates and said platen, a clamp adapted to hold any sheet while being so threaded, and rolls adapted to bear against the faces of the carbon sheets, so that only the backs of the carbon sheets bear against said angle plates.
26. In a typewriting machine, the combination with a traveling carriage and a rotatable platen therein, of a rearward extension of said carriage, means on said extension adapted to removably support angle plates projecting alternately from the opposite sides of said extension, a second extension of said carriage projecting nearly upwardly, and thumb-screws and collars adapted to support angle plates projecting alternately from the opposite sides of support, so that all said angle plates may extend into the folds of a fan-fold web.
27. In a typewriting machine, the combination with a traveling carriage and a rotatable platen therein, of a rearward extension of said carriage, means on said extension adapted to removably support angle plates projecting alternately from the opposite sides of said extension, a second extension of said carriage projecting nearly upwardly, thumb-screws and collars adapted to support angle plates projecting alternately from the opposite sides of said second extension, so that all said angle plates extend into the folds of a fan-fold web, and means above said second extension for measuring and cutting the fan-fold web.
28. In a typewriting machine, the combination of a traveling carriage and a rotatable platen therein, of means for holding work-sheets against said platen, an angle plate adapted to feed a carbon sheet in between said work-sheets to permit the carbon

sheet to be fed with said work-sheets in a line parallel with the axle of the platen, a second angle plate extending between said work-sheets beyond the printing point at the 5 platen, to lead the carbon sheet away from the work-sheets, a guide to carry the carbon sheet back to the first plate so that a continuous carbon sheet belt may be employed,

and an axle for said platen having an interruptible portion to permit the bight of 10 the belt to be inserted between said platen and said holding means.

ARTHUR A. JOHNSON.
